CLAIM

The ornamental design for a set of mop squeezer, as shown and described.

DESCRIPTION

- 1.1 right side view of the set of mop squeezer;
- 1.2 left side view thereof;
- 1.3 back view thereof;
- 1.4 front view thereof;
- 1.5 top plan view thereof;
- 1.6 bottom plan view thereof;
- 1.7 front perspective view thereof;
- 1.8 front view of component one of the set of mop squeezer;
- 1.9 back view thereof;
- 1.10 right side view thereof;
- 1.11 left side view thereof;
- 1.12 bottom view thereof;
- 1.13 top plan view thereof;
- 1.14 front perspective view thereof;
- 1.15 front view of component two of the set of mop squeezer;
- 1.16 back view thereof;
- 1.17 right view thereof;
- 1.18 left view thereof;
- 1.19 top plan view thereof;
- 1.20 bottom plan view; and
- 1.21 back perspective view thereof.
